UNITED STATES PATENT OFFICE.

RICHARD H. WELLES, OF KENOSHA, WISCONSIN, ASSIGNOR TO BADGER BRASS MFG. CO., OF KENOSHA, WISCONSIN, A CORPORATION OF WISCONSIN.

DESIGN FOR A TAIL-LAMP.

46,270.

Specification for Design.

Patented Aug. 11, 1914.

Application filed June 5, 1914. Serial No. 843,312. Term of patent 7 years.

To all whom it may concern:

Be it known that I, RICHARD H. WELLES, a citizen of the United States, and a resident of Kenosha, in the county of Kenosha and State of Wisconsin, have invented a new, original, and ornamental Design for a Tail-Lamp, of which the following is a specification, reference being had to the accompanying drawings, forming a part thereof.

In the drawings Figure 1 is a front elevation of my new design; Fig. 2 is an under side view looking vertically upward at the bottom of Fig. 1; and Fig. 3 is a side elevation looking at Fig. 1 from the right-hand side.

The salient or distinguishing features of the design may be briefly described as follows: A flat rear plate upon which is mounted a polygonal body having straight

sides substantially at right-angles to the back plate and terminating in the front in a rounded lens opening. The lens opening is surrounded by a circular bead the base of which springs from the polygonal front of the body. Downward illumination is supplied by light passing out of the glazing openings at the bottom of the lamp, and, when the lamp is lighted, this gives the lamp a very attractive and esthetic appearance.

I claim—

The ornamental design for a tail lamp as shown and described.

RICHARD H. WELLES.
